UNITED STATES PATENT OFFICE

STEPHEN WARD BALKWILL, OF CLEVELAND HEIGHTS, OHIO

RAILWAY CROSSING

Application filed March 24, 1930. Serial No. 438,333.

My invention, relating as indicated to railway crossings, has specific reference to improvements in articulated crossings, more especially crossings of the type illustrated and described in Patent No. 1,233,437, dated July 17, 1917. The advantages of the use of articulated crossings, as compared to those of the common form of solid crossing, are so well known to those familiar with the art that a reiteration thereof at this point is believed unnecessary. My invention is specifically directed to improvements in articulated crossings, which improvements have to do primarily with the formation of the various elements so that a crossing of improved design results, having the further advantages of simplicity of construction which has not been possible with forms heretofore employed. It is among the objects of my invention to provide a crossing which shall have the above named desirable characteristics. Other objects of my invention will appear as the description proceeds.

To the accomplishment of the foregoing and related ends, said invention, then, consists of the means hereinafter fully described and particularly pointed out in the claims; the annexed drawing and the following description setting forth in detail certain mechanism embodying the invention, such disclosed means constituting, however, but one of various mechanical forms in which the principle of the invention may be used.

In said annexed drawing:

Fig. 1 is a plan view of an articulated crossing embodying the improvements of my invention; Fig. 2 is a transverse sectional elevation of an approach of the crossing illustrated in Fig. 1 taken on a plane substantially indicated by the line 2-2; Fig. 3 is a transverse sectional elevation of an approach taken on a plane substantially indicated by the line 3-3; and Fig. 4 is a transverse sectional elevation of an approach taken on a plane substantially indicated by the line 4-4.

Referring more specifically to the drawings and more especially to Fig. 1, the crossing here shown is of the type wherein the intersecting grooves or flangeways intersect at

right angles to each other, although it should be noted that the principles comprising my invention are equally applicable to crossings other than the rectangular type here chosen for purposes of illustration.

The crossing, as indicated in Fig. 1, consists of four substantially U-shaped elements 1 which are adapted to be interconnected by means of angle shaped members 2 occupying the outer corners between the legs 3 of the U-shaped members 1. The inner corners between the contiguous corners of the U-shaped members 1 are filled by knee brace elements 4 which, along with the angle elements 2 and the U-shaped members 1, are suitably bolted together by means of bolts as at 5 to form a rigid structure capable of withstanding the rigid service to which such crossing is subjected. The lateral faces of the U-shaped members 1, more especially the legs 3 thereof, are formed with longitudinally tapering grooves 6 which terminate at one end as at 7 at those points of the inner faces of the U-shaped elements 1 which are engaged by the outer corners of the knee brace members 4. The opposite terminal portions 8 of the grooves 6 may terminate in a vertical line which is coincidental with one corner of the rail receiving aperture in the approach to the crossing, as hereinafter more fully described.

The approaches to the crossing, and I here prefer to employ the term approach as meaning that portion of the crossing by which the wheels of the cars either enter upon or leave the crossing, depending upon the direction of movement of the train, are formed by the bolting together of the angle members 2 and the legs 3 of the U-shaped elements 1. Terminally formed in the legs 3 of the U-shaped elements 1 and the legs 9 of the angle members 2 are rail receiving recesses formed in the manner hereinafter described. Extending from the inner terminus of the rail receiving aperture in the legs 9 of the angle element 2 and projecting laterally from the longitudinal faces 10 thereof are tapered flanges or tongues 11 which are formed complementary to the taper of the grooves 6 and which terminate as at 12, which point may

occupy a position adjacent to the outer corner of the knee braces 4 when the various elements of the crossing are bolted together.

The rail receiving apertures generally indicated at 13, and which are formed by the contiguous legs 3 and 9 of the elements 1 and 2 respectively, have lateral walls or faces 14 and 15, respectively formed on the terminals of the legs 3 and 9. The inner 10 terminus of the preferably flat face 14 may coincide with the vertical line 8 which is the outer terminus of the groove or slot 6 and the outer terminus of the flange or tongue 11, which is indicated at 15, and may likewise 15 coincide with the vertical line 8 when the members are in assembled relation. The flat face 15 formed interiorly of the terminal portion of the leg 9 extends substantially parallel with the axis of the rail adapted to be 20 mounted in the receiving aperture 13 while the face 14 preferably converges outwardly from the line 8 so that a suitable wedge member 16 may be introduced between the rail 17 and the face 14 of the arm 3, thereby insuring 25 a close fitting construction when the parts are bolted together. The legs 3 and 9 have respectively integrally formed therewith at their lower inner edges inwardly disposed flange members 18 and 19 which extend the length of the aperture 13. When the 30 rail 17 is positioned in the receiving aperture 13 formed therefor, a base plate 20 may be interposed between the bottom of the rail 17 and the flanges 18 and 19 to afford a re- 35 placeable wearing element between the rail and the crossing proper. Interposed between the web of the rail and the face 15 of the arm 9 is a longitudinally extending filler member 21 which provides additional means 40 for supporting the rail in the approach when the bolts 5 are put in place and the nuts 22 thereof made tight.

It will be noted in connection with the construction of the approaches, as illustrated by the sectional views 2 and 3, that the flange or tongue 11 which engages the groove 6 is preferably formed in the manner more specifically shown in Fig. 3, and the under portion 45 of the arm 9 of angle member 2 may be hollow and provided with transversely extending bolt supporting cord elements 23.

The principles of construction hereinbefore described comprising my invention are particularly advantageous when the crossing is 50 assembled or disassembled due to the fact that any one rail may be secured to or removed from the crossing by disturbing only those bolts which pass through the rail and without disassembling any other parts of the 55 crossing. Further, the formation of the grooves 6 and the engaging flanges 11 is such that particular advantages of construction are presented which are not found in any forms of construction heretofore employed.

65 It is believed that a further description of my

invention is unnecessary for those acquainted with the art. Suffice it to say that numerous advantages result from the employment of the construction above described and that by its use a crossing will result having qualities 70 superior to any heretofore constructed.

Other modes of applying the principle of my invention may be employed instead of the one explained, change being made as regards the mechanism herein disclosed, provided the 75 means stated by any of the following claims or the equivalent of such stated means be employed.

I therefore particularly point out and distinctly claim as my invention:—

1. In a railway crossing, the combination of a plurality of members which when assembled have intersecting grooves formed in their top surfaces, rail receiving apertures formed in the approaches of the crossing, and complementary interengaging means on the contiguous faces of said members, said last named means tapered longitudinally and terminating in said rail receiving apertures. 85

2. In a railway crossing, the combination of a plurality of members which when assembled have intersecting grooves formed in their top surfaces, rail receiving apertures formed in the approaches of the crossing, and complementary interengaging means on the 90 contiguous faces of said members, said interengaging means tapered longitudinally and extending from the terminals of said rail receiving apertures. 95

3. In a railway crossing, the combination of a plurality of members which when assembled have intersecting grooves formed in their top surfaces, rail receiving apertures formed in the approaches of the crossing, and complementary tongue and groove means associated with said members, said tongue and groove means tapered longitudinally and terminating in said receiving apertures. 100

4. In a railway crossing, the combination of a plurality of members which when assembled have intersecting grooves formed in their top surfaces, rail receiving apertures formed in the approaches of the crossing, and complementary tongue and groove means associated with said members, said tongue and groove means extending from the terminals of said rail receiving apertures toward the intersection of said grooves. 110

5. In a railway crossing, the combination of a plurality of members which when assembled have intersecting grooves formed in their top surfaces, rail receiving apertures formed in the approaches of the crossing, and complementary tongue and groove means formed integrally with the adjacent faces of 115 said members and extending from the terminals of said rail receiving apertures to points adjacent the intersection of said grooves. 120

6. In a railway crossing, the combination of a plurality of members which when assem- 125

bled have intersecting grooves formed in their top surfaces, rail receiving apertures formed in the approaches of the crossing, and complementary interengaging means on the contiguous faces of said members, said last named means tapered longitudinally and extending from the terminals of the sides of said rail receiving apertures.

7. In a railway crossing, the combination of a plurality of members which when assembled have intersecting grooves formed in their top surfaces, rail receiving apertures having non-parallel sides formed in the approaches of the crossing, and complementary interengaging means on the contiguous faces of said members, said last named means tapered longitudinally and extending from the terminals of the sides of said rail receiving apertures.

10. In a railway crossing, the combination of a plurality of members which when assembled have intersecting grooves formed in their top surfaces, rail receiving apertures having flat non-parallel sides formed in the approaches of the crossing, and complementary interengaging means on the contiguous faces of said members, said last named means tapered longitudinally and extending from the terminals of the sides of said rail receiving apertures.

15. In a railway crossing, the combination of a plurality of members which when assembled have intersecting grooves formed in their top surfaces, rail receiving apertures having relatively outwardly converging sides formed in the approaches of the crossing, and complementary tongue and groove interengaging means associated with said members, said last named means tapered longitudinally and extending from the terminals of the sides of said rail receiving apertures.

20. In a railway crossing, the combination of a plurality of members which when assembled have intersecting grooves formed in their top surfaces, rail receiving apertures having relatively outwardly converging sides formed in the approaches of the crossing, and complementary tongue and groove interengaging means associated with said members, said grooves and one of said sides oppositely tapered from a common line.

Signed by me, this 22d day of March, 1930.
STEPHEN WARD BALKWILL.
